UNITED STATES PATENT OFFICE.

WILHELM GROENEBAUM, OF NEU-BABELSBERG, NEAR BERLIN, GERMANY, ASSIGNOR
TO THE FIRM NAAMLOZE VENNOOTSCHAP FINANCIËLE MAATSCHAPPIJ "DRIE-
BERGEN," OF SCHEVENINGEN, NETHERLANDS.

RECORD CYLINDER CARRIER OF SPEECH RECORDING OR REPRODUCING MACHINES.

Application filed March 5, 1925, Serial No. 13,083, and in Germany January 28, 1925.

This invention relates to a method of manufacture and a construction of drum for carrying the record cylinders of speech recording or reproducing machines, such as phonographs, and telephonographs. The drums used hitherto are defective inasmuch as, they being necessarily of different material from the record cylinders, variations of temperature cause the record cylinders to bind upon the drums or to become loose. As a rule, the drum is made of metal, preferably aluminium, while the record cylinder usually consists of wax. The coefficients of expansion of these materials are very different, so that if the record cylinder is put on at ordinary room temperature it will bind if the temperature falls, and become loose if the temperature rises, thus interfering with the use or operation of the machine. The cause of this defect is the lack of resilience in the contacting parts, which do not yield sufficiently to allow for the difference in expansion due to the temperature changes. Based on this discovery, the invention comprises a drum for carrying record cylinders which has yielding, resilient walls, and a surface of particular form, which ensures that records can be put on and taken off from and held firmly on the drum irrespective of changes of temperature. According to the invention, a cylindrical or commonly a slightly coned hollow drum is slotted longitudinally to make its walls flexible, and is somewhat swelled out in the middle, i. e. made slightly barrel-shaped, by a new method hereinafter described.

The invention is explained with reference to the accompanying drawing.

Figure 1 shows in longitudinal section a drum ready for subjection to the new method of manufacture.

Figure 2 shows a section on the line 2—2 of Figure 1.

Figure 3 shows an axial section of a finished drum.

The drum is suitably formed of a hollow body 1 which may have or may be machined to have either a cylindrical or a slightly coned surface, to facilitate record cylinders being put on. End discs 2^a, 2^b are fastened upon the drum for mounting it, and on them are pivots 3 to be held in bearings. The surface of the body 1 is worked to near its final dimensions, and in the case of a

conical surface the diameter at the end disc 2^a will be a little smaller than at the end disc 2^b.

In order to bow out the middle of the surface, the following method is adopted: About in the middle of its length, a shallow circumferential groove 4 of suitable width is turned. To make the walls of the drum yielding and resilient narrow longitudinal slots 5 are cut in them. A compression ring 6, which may suitably be made in two halves with flanges 7 for bolting them together, is placed around the body 1 in the groove 4. The width of the ring 6 may suitably be equal to, and must not be greater than, the width of the groove 4. The inner diameter of the ring is somewhat less than the diameter of the groove 4. When the flanges are drawn together by tightening the bolts 8, the walls of the body 1 are pressed inward to a determined extent in the middle. The surface of the body 1 is then finished, the compression ring 6 not being in the way during this operation since the surface does not need to be further worked where it is grooved. The surface is first turned to a cylindrical or slightly conical form, having however straight line generators, and to such a size as adapts the external diameter of the ends of the drum to the internal diameter of the record cylinders to be mounted on it; while the remainder of the external surface of the drum is fitted to the internal measurements of the cylinders which only have a spiral rib on their inner surface to form a seating upon the drum. Finally the surface of the drum is polished.

When the compression ring 6 is removed, in consequence of the resilient walls of the drum having been compressed during machining, the middle part of the surface swells out, as indicated in Figure 3. In this figure the broken line 9 indicates the form prior to removal of the compression ring, and makes clear the nature of the swelling.

When a record is pushed on to a drum so constructed, its walls can yield resiliently. The record is therefore held firmly in place. If the temperature changes the walls of the drum can yield because of the slots 5, so that the record does not become fast on the drum, but can easily be removed or put on at any temperature.

The groove 4 should, in the first instance, be of such depth that the adjacent finished surface of the drum is preferably only of slightly larger diameter than the outer diameter of the drum at the groove; or at any rate so that said adjacent finished surface is not of lesser diameter than the diameter at the groove. That is to say, at the end of the finishing operation, the portions of the drum adjacent to the groove should project outwardly beyond the bottom of the groove 4 to a minimum extent, and in no case should said portions be less than flush with said bottom of the groove. In other words, the wall of the drum should be as thin as possible with respect to the groove 4, in order that the desired elasticity may be developed in the drum.

The invention is not confined to the method of manufacture described, but comprises the form of drum itself. Its essential characteristic is that the surface of a cylindrical or slightly conical body is slit lengthwise to give flexibility, and is made somewhat barrel-shaped. Drums made according to the method described above as a way of carrying out the invention are recognizable by the shallow groove around them approximately in the middle, where the compression ring has been placed.

I claim:

1. A carrier for the record cylinders of speech recording and reproducing machines, comprising a hollow body having an outer surface of revolution generated by a line slightly bowed in a direction away from the axis of revolution, the walls of said body being slit longitudinally.

2. A carrier for the record cylinders of speech recording and reproducing machines, comprising a hollow metal body provided with longitudinal slits having their opposite ends closed, said slits extending lengthwise of the body, to divide the latter into a plurality of strips, the latter curving outwardly intermediate their ends to impart an outwardly bulging form to said drum in its normal condition.

3. A carrier for the record cylinders of speech recording and reproducing machines,

comprising a slightly barrel-shaped body composed of resilient longitudinal strips and discs to which the opposite ends of said body are secured, said discs being adapted for rotation in bearings.

55

4. A carrier for the record cylinders of speech recording and reproducing machines, comprising a substantially cylindrical hollow metal body having its outer surface slightly barrel-shaped, having longitudinal slots extending over a part of its length, and having the thickness of its walls tapering from an intermediate point of the body towards the opposite ends thereof.

60

5. A carrier for the record cylinders of speech recording and reproducing machines, comprising a substantially cylindrical hollow metal body, having its outer surface slightly barrel-shaped, having longitudinal slots extending over a part of its length, and having a shallow circumferential groove intermediate its ends.

65

6. A method of manufacturing record carriers for sound recording and reproducing machines, which consists in grooving a substantially cylindrical hollow body circumferentially at about its middle, slotting said body longitudinally through a portion of its length, constricting said body by means of a band in the groove, and turning said body by a rectilinearly moving tool while so constricted.

75

7. A method of manufacturing record carriers for sound recording and reproducing machines, which consists in slotting a substantially cylindrical hollow body longitudinally, constricting said body circumferentially intermediate its ends, and machining said body by a rectilinearly moving tool while so constricted.

85

8. A method of manufacturing record carriers for sound recording and reproducing machines, which consists in slotting a substantially cylindrical hollow body longitudinally, and machining said body to taper its outer surface from an intermediate point toward its opposite ends.
